UNITED STATES PATENT OFFICE

2,510,804

BRUSH WITH DETACHABLE FITTING FOR
BRISTLE-CARRYING STOCKS

Eric Leopold Hugo Cosby, London, England

Application November 15, 1946, Serial No. 710,113
In Great Britain April 19, 1945Section 1, Public Law 690, August 8, 1946
Patent expires April 19, 1965

2 Claims. (Cl. 15—176)

1

The invention relates to that class of brush in which the stock carrying the bristles is detachably secured to the back, and whereby the stock can be inserted and held in the back in either of two directions, such as is described in United States Patent No. 2,228,754.

The object of the present invention is to improve the construction of such class of brush whereby the back can be lightened in weight and to allow of the back being constructed of plastic or other mouldable or castable material, further to simplify the catch means for securing the stock to the back.

According to this invention, the bottom of the recess in the back of the brush for receiving the catch fitting is hollowed-out or recessed to leave a platform or ledge on which the catch fitting rests and in which the securing screws can be engaged, a pin or stud is provided on the platform, shoulders or locating stops are provided in the hollowed-out or recessed portion positioned at a distance apart, lugs or projections are provided on the under-face of the catch fitting adapted to be located between the shoulders or locating stops, and a hole is provided in the catch fitting for engaging with the pin or stud in the back.

The invention will be clearly understood from the following description aided by the accompanying drawings, in which:

Figure 1 is a plan of one construction of back. Figure 2 is a section on the line II—II of Figure 1. Figure 3 is a section on the line III—III of Figure 1. Figure 4 is a plan of the catch fitting. Figure 5 is an under-plan of same, and Figure 6 a view similar to Figure 2 with the catch fitting located in the back.

The invention can be carried into effect in various ways as to detailed construction. According to this example, the back 1 is formed with a recess of a shape corresponding to the shape of the catch fitting. Said recess is surrounded by a wall 2, the bottom of the recess forming a platform 3 or support to which the catch fitting is secured by screws passing through holes 4 in the catch fitting (Figures 4 and 5) engaging in holes 5 in the platform 3.

The platform 3 or bottom of the recess is hollowed-out or recessed as at 6 to any suitable shape so as to leave side edges of a ledge for supporting the catch fitting and to receive the screw holes 5. At a little distance from the forward end the platform 3 is shaped to form two parallel shoulders 7 or locating stops at a suitable distance apart. On the rear end of the

2

platform 3 is an upstanding pin 8 or stud of less height than the depth of the wall 2 and in the forward end of the wall 2 is formed the usual hole 9 or slot. The handle 10 is preferably formed with a tapering groove 11 on one or both sides to form a grip for receiving the fingers when the handle is grasped in the hand, and also for reducing the weight of the back.

The catch fitting may be of any suitable construction formed with a hole 12 for engaging with the pin 8, and projecting lugs 13 or stops for engaging between the shoulders 7 when the fitting is positioned in the recess in the back 1, the pin 8 taking part of the strain of the fitting in the back and the lugs 13 and shoulders 7 aligning and retaining the fitting in proper position.

Preferably the catch fitting comprises a plate 14 or liner having a wall 15 around its edge, and in the plate 14 is formed a hollow raised flat portion 16 of less area than the area of the plate 14, and connecting one end of the raised portion 16 with the edge of the plate 14 is a central raised panel or strip 17. At the other end of the raised portion 16 are two diagonal panels 18 or strips, the panels or strips 17, 18 being of slightly less height than the top of the portion 16 and with their upper surfaces in the same plane. In the raised portion 16 is formed a slot 19 or opening similar to the construction described in Patent No. 2,228,754.

To the underside of the plate 14 is secured an under-plate 20 longitudinally and centrally, the under-plate 20 being conveniently secured to the plate 14 by tongues 21 punched out of the plate 14 and bent over the edge of the under-plate 20. The lugs 13 may also be punched out of the under-plate 20 and bent to be at right angles to the under-plate 20 and in parallel planes.

In connection with same is a slidable flat bar 22 having a punched up catch 23 or hook projecting through the slot 19 in the plate 14, the bar 22 having a shank 24. The rear end of the bar 22 is formed with a bent up lug 25, and the forward end of the under-plate 20 is formed with a similar bent up lug 26, the two lugs being connected by a tension spring 27 so that the bar 22 is normally urged forwards in the fitting, the under-plate 20 being formed with a longitudinal slot 28 from the rear end in which the lug 25 works.

The stock with its bristles is constructed in a similar manner to the stock previously proposed, such as for instance in Patent No. 2,228,754 and is secured in the fitting 14.

The catch fitting is positioned in the recess in the back 1 with the shank 24 projecting through the hole 9 and with the hole 12 engaging over the pin 8, the lugs 13, 13 being located between the shoulders 7, 7 and secured therein by screws passing through the holes 4 in the fitting into the holes 5 in the back.

It will be understood that the back 1 can be constructed without the extending handle 10.

What I claim as my invention is:

1. A brush comprising a back having a recess therein, and a catch fitting including a spring-urged slideable catch device for detachably securing a bristle carrying stock to the back, the bottom of the recess in the back having a hollowed out portion forming a ledge on which the fitting rests, securing screws for said fitting engageable in said ledge, a pin on said ledge, locating stops in said hollowed out portion at a distance apart, and projections on the underside of the catch fitting adapted to be positioned between said locating stops, said fitting having a hole therein to receive said pin on said ledge.

2. A brush as defined in claim 1, wherein said

catch fitting comprises a plate having a wall around its edge and a raised central portion having an opening therein, and an under-plate secured to said plate and having a slot therein, and said catch device comprises a flat bar having a hook projecting through said opening in said hollow raised portion and being slidably held between said plate and under-plate, a shank on said bar projecting beyond the catch fitting, a lug on said bar located in said slot in the under-plate, a lug on said under-plate, a tension spring connecting said lugs, and bent-up tongues on said under-plate engageable between said locating stops in said hollowed out portion of the back.
